RADIO BEACON AND RADIO GUIDE

Yves Rocard, Paris, France, assignor to Compagnie Générale de Télégraphie Sans Fil, a corporation of France

Application April 30, 1938, Serial No. 205,247
In France May 21, 1937

7 Claims. (Cl. 250—11)

The present invention aims at providing a vehicle (aircraft, ship, etc.) receiving a radio guide signal, with indications of the position relative to the axis marked by the radio guide and which are more precise than those furnished by the systems known as such.

It is known that among radio guides with interlocking signals there exist two principal types, the one which marks from a point two directions, thus providing one kind of signals (dots for instance) in an entire sector in space, and another kind of signals (dashes for instance) appearing in the entire complementary sector, the other principal type of guide, however, marks four directions and divides the space into four sectors whereby two that are diametrically opposite are characterized by dots and the other two by dashes.

It can be seen directly that the beacon of the first type furnishes a signaling without ambiguity but an incomplete signaling whereby the pilot knows whether he is on the one side or other side of the course but does not know whether or not he has passed the transmitter, whereas beacons of the second type furnish a more complete signaling but with a certain ambiguity and when the pilot hears dots, for instance, he has no way of discerning in which of the sectors having the dots he finds himself.

The invention relates to means for remedying these drawbacks. It resides in providing a radio beacon transmitter which can pass from one type of signaling (two directions) to the other one (four directions) whereby two of the four directions of the second operating mode coincide with one of the two directions of the first mode and using this beacon during a large part of the time (for instance, for 16 seconds within a time period of 20 seconds) for one of the operating modes, preferably the signaling of the two directions and the rest of the time (in the present case 4 seconds) for the other operating mode (signaling of four directions) by effecting simultaneously any sort of change in the beacon transmitter (for instance the change of the low modulation frequency note) in passing from the first to the second operating mode so that the pilot knows through this change which signal is being sent to him.

The functioning of the device according to the invention will be better understood in reference to the accompanying figures.

Figure 1 represents schematically in a plan view the marking of the type of two opposite directions from the beacon transmitter R;

Figure 2 shows likewise the marking of the type of four directions;

Figure 3 represents the signals obtained from the beacon transmitter according to the invention;

Figures 4a to 4c represent the radiation diagrams of the aerials used in one mode of embodiment of the idea of the invention; and

Figure 5 shows schematically the arrangement of the antennas and the switches to be used.

If a radio guide system functions in accordance with the scheme of Fig. 1, the pilot when in the region A hears dots and in the region B hears dashes while the two main regions C represent the axis in which he hears a continuous note.

If a radio guide system operates, however, according to the scheme of Fig. 2, the region of dots is A₁ (two sectors), that of dashes is B₁ (two sectors), and that of the continuous note is C₁ formed by four sectors of which two, for instance shall be very narrow and the other two very wide.

Fig. 3 represents the signals heard by the pilot listening to a beacon transmitter according to the invention which operates according to the type of Fig. 1 with the modulation note n₁ (say 400 cycles) for 16 seconds, for instance, and, according to the type of Fig. 2, with the modulation note n₂ (say 2000 cycles) during 4 seconds. The figure shows in solid and black characters the signals during 16 seconds with the frequency n₁ and in blank characters bordered by lines the signals during 4 seconds with the frequency n₂.

It will be seen that if the airplane is on the axis C₂, the pilot will observe a continuous signal whose frequency will change only during 4 seconds three times per minute, while if the airplane is outside this axis the pilot will know (provided the plane remains in this same sector at least 20 seconds) in which region among the six regions A₂ A₃ A₄ B₂ B₃ B₄ he finds himself, these regions being characterized respectively as follows:

A₂ by hearing dots n₁ and also dots n₂

A₃ by hearing dots n₁ and a continuous note n₂

A₄ by hearing dots n₁ and dashes n₂

B₂ by hearing dashes n₁ and also dashes n₂

B₃ by hearing dashes n₁ and a continuous note n₂

B₄ by hearing dashes n₁ and dots n₂

A practical embodiment of the idea of the invention will be given in the following, by way of example.

Referring to Figs. 4a, 4b, 4c and 5 an aerial 10, 10' is provided furnishing a figure of 8 dia-

gram having two fields of opposite instantaneous polarity which produce zero radiation in the direction OC, Fig. 4a, this diagram being obtained by known means and especially in the case of 5 short waves, by a system of two doublets lined up in a plane perpendicular to OC and fed by opposite currents. The phase of these currents will be reversed by switch M1 in the rhythm of the dots and dashes thus providing the signals of the 10 transmitter, as will subsequently appear. A second aerial 11, 11' is furthermore provided and constantly fed and capable of furnishing by means of simple modification either a modified figure 8 diagram having an identical instantaneous phase of radiation in all directions as 15 shown in Fig. 4b or a figure of 8 diagram as shown in Fig. 4c, having a pair of fields of opposite instantaneous polarity and a direction of zero radiation at 90° to OC. The currents feeding 20 doublets 11, 11' are not switched at the dot and dash rhythm. In order to obtain these effects, this second aerial is formed of two doublets 11, 11' lined up in a vertical plane parallel to OC and spaced apart slightly less than one-half wave. 25 It will, moreover, be sufficient to feed these two doublets in parallel for obtaining the modified figure 8 diagram of Fig. 4b or in opposition for the figure of 8 diagram of Fig. 4c. The resultant field is the vector sum of the field of 30 Fig. 4a and either the field represented by Fig. 4b or 4c, depending upon the position of the reversing switch J. In one position of the switch, which may be maintained for 16 seconds, for example, the fields represented by Figs. 4a and 4b 35 are combined to produce a beacon in accordance with Fig. 1, while in the other position of the switch, which may be maintained for 4 seconds, for example, the fields represented by Figs. 4a and 4c are combined to produce a beacon in accordance with Fig. 2. At the same time, the 40 phase of the current feeding the doublet system 10, 10' is reversed with respect to the current feeding the doublet 11, 11' at a keying rate to produce characteristic signals. The requirements of the system of Fig. 3 are thus satisfied. 45 The fields supplied by the two doublets 10, 10' and 11, 11' are expressed respectively for each doublet, designating by d the distance between doublets and by θ the azimuths, by

$$\sin(\omega t + \frac{\pi d}{\lambda} \sin \theta) \quad (1)$$

and

$$\sin(\omega t - \frac{\pi d}{\lambda} \sin \theta) \quad (2)$$

If the doublets are fed in opposition (case of the system 10, 10' and the system 11, 11' in position illustrated in Fig. 4c, it is necessary to subtract the expressions (1) and (2), and the difference is transformed into:

$$2 \cos \omega t \sin \frac{\pi d}{\lambda} \sin \theta \quad (3)$$

65 The field is therefore proportional to the term

$$\sin \left(\frac{\pi d}{\lambda} \sin \theta \right)$$

70 and it is zero for $\theta=0$ and $\theta=\pi$. The diagram has accordingly always two loops, the phase in one of these loops being opposite to the phase in the other loop. The shape of the loops is influenced by the factor

$$\frac{\pi d}{\lambda}$$

but this influence is fairly small within fairly wide limits. For

$$d = \frac{\lambda}{2}$$

or in the neighborhood of this value, it may be admitted that the loops are materially circular.

The interruptor switch M1 being maneuvered alternatively in a manner to be in one of its positions for the duration of one dot and in the inverse position for the duration of one dash, the fields supplied by system 10, 10' will have the shape shown in Fig. 4a in each of these positions, but the polarity will be alternately reversed. One of the loops of the diagram has been indicated with dotted line to show that its polarity is opposite to that of the loop in full line. Likewise, the diagram of Fig. 4c represents the shape of the field of system 11, 11' in one position of switch J, and the polarity of this diagram is never switched, and it is supposed that each loop of the diagram is in phase with a loop of the diagram of Fig. 4a.

In the other position of switch J, the elementary doublets 11, 11' are fed in phase as shown in Fig. 4b and it is necessary to form the sum of the terms (1) and (2) which are reduced to:

$$2 \sin \omega t \cos \left(\frac{\pi d}{\lambda} \sin \theta \right) \quad (4)$$

The field is thus proportional to the term

$$\cos \left(\frac{\pi d}{\lambda} \sin \theta \right)$$

it is seen that if

$$d = \frac{\lambda}{2}$$

the field is zero for

$$\theta = \frac{\pi}{2}$$

and the diagram has two loops exactly as the diagram of Fig. 4c but if d be slightly lower than

$$\frac{\lambda}{2}$$

45 the term in question will be always positive and in phase in all directions.

The conditions of Fig. 1 are realized by the combination of the diagrams of the system of Fig. 4a and of the system of Fig. 4b. The diagrams are combined in effect into a species of cardioid L, Fig. 1, the phases being added for the loop in full line and being subtracted for the loop in dotted line. Likewise, after inversion of phase, the diagrams of Figs. 4a and 4b are combined into an inverted cardioid L1. The intersection of the cardioids L and L1, alternated to the cadence of the dots and dashes, supplies two routes C characterized by a continuous dash.

Likewise, the conditions of Figure 2 are realized by the combination of the diagrams of Fig. 4a and of system 4c. The diagrams illustrated are combined into a diagram with two loops F and F1, Fig. 2, the phases being added in the loops in full line of the two diagrams, and being added likewise in the loops in dotted line. In the same manner, after inversion of phase of system 10, 10', the diagrams are combined into two loops G and G1, and the intersection of the diagrams F, F1 and G, G1, alternated to the cadence of the dots and dashes, supplies four routes characterized by continuous dashes.

It should, furthermore, be noted that in order to obtain signals furnishing the maxi-

mum of clarity with axes presenting the maximum of fineness the phase of the currents feeding the two doublets 10, 10' should be in quadrature with the currents feeding the doublets 11, 11' when operating in the position corresponding to Fig. 4b, and should be the same phase (or in phase opposition) when operating in the position B corresponding to Fig. 4c. This, thus, requires that if the maximum clearness of the signals is desired,

10 a variation of

$$\frac{\pi}{2}$$

15 of the phase difference of the currents in 10, 10' and 11, 11' must be assured at the moment of passing from one transmission pattern to the other.

Fig. 5 shows a gain, by way of example, to which the invention is not limited, an assembly of the 20 possible arrangement of the aerials and their feeders. A switch M1 provides the reversing of the phase in the rhythm of the dashes and dots in the antennas 10, 10', a reversing means j and a contact means c provide, respectively, the 25 transition from modified figure 8 to figure of 8 transmission and the adjustment of the phase (depending on whether or not a portion of the feeder equal to

$$\frac{\lambda}{4}$$

30 is short circuited) of the antennas 11, 11' in the very slow rhythm of passing from the two-course to the four-course transmission at the rate of 16 35 seconds to 4 seconds, for instance.

The two distinct modulating frequencies n_1 and n_2 , referred to above, are provided by alternators P and Q which are alternately connected to a carrier frequency generator S through a 40 switch K which is operatively connected to the reversing switch J and the short circuiting switch C. The switches may be driven by a motor K at the desired rate. The switch M1 is driven at the keying rate by a keying motor N.

In reality, it is necessary to carry out this 45 phase adjustment when passing from the transmission of Fig. 4b to that of Fig. 4c because a phase detuning θ near 45° can well be tolerated in the position represented by Fig. 4b relative to optimum phase of the aerial 11, 11' without notably disturbing the clearness of the signals. 50 However, when passing from the position represented by Fig. 4b to that of Fig. 4c a phase detuning

$$\frac{\pi}{2} - \phi$$

55 which is near 80° will be produced automatically due to the impedance change resulting from the change of connections.

60 What I claim is:

1. Radio-guide transmitting system comprising a first aerial having a vertical symmetry axis, means for transmitting by said first aerial a figure 8 radiation field, means for reversing the 65 phase of said field at dot and dash rhythm, a second aerial having a common vertical symmetry axis with said first aerial, and means including switching means connected to said second aerial for transmitting by said second aerial alternatively a radiation field having identical instantaneous phase in all directions, and a figure 8 radiation field analogous to that of said first aerial but perpendicular thereto.

70 2. Radio-guide transmitting system comprising a first aerial having a vertical symmetry axis,

means for transmitting by said first aerial a figure of 8 radiation field, means for reversing the phase of said field at dot and dash rhythm, a second aerial having a common vertical symmetry axis with said first aerial, and means including switching means connected to said second aerial for transmitting by said second aerial alternatively a radiation field having identical instantaneous phase in all directions, and a figure 8 type field analogous to that of said first 10 aerial but perpendicular to the latter, the duration of said transmissions being unequal.

3. Radio-guide transmitting system comprising a first aerial having a vertical symmetry axis, means for transmitting by said first aerial a figure of 8 type radiation field, means for reversing the phase of said field at dot and dash rhythm, a second aerial having a common vertical symmetry axis with said first aerial, and means including switching means connected to said second aerial for transmitting by said second aerial alternatively a radiation field having identical instantaneous phase in all directions, and a figure of 8 radiation field analogous to that of said first aerial but perpendicular thereto, 15 means for feeding said aerials by a modulated high frequency current, and means for changing the modulation frequency synchronously with the switching of said fields produced by the second aerial.

4. Radio-guide transmitting system comprising a first aerial constituted of two vertical doublets disposed at a predetermined distance about a symmetry point, means for feeding said doublets in phase opposition, means for reversing the feeding phase of said doublets at dot and dash rhythm, a second aerial having a vertical symmetry axis in the said symmetry point, and means including switching means connected to said second aerial for transmitting by said second aerial alternatively a modified figure 8 radiation field having identical instantaneous phase in all directions, and a figure of 8 radiation field analogous to that of said first aerial but perpendicular thereto.

5. Radio-guide transmitting system comprising a first aerial having a vertical symmetry axis, means for transmitting by said first aerial a figure of 8 type radiation diagram, means for reversing the phase of said field at dot and dash rhythm, a second aerial constituted of two vertical doublets separated by a distance slightly less than a half wavelength of radiated energy and disposed symmetrically about said symmetry axis of the first aerial, and switching means for 50 changing feeding connections of said doublets so as to feed them alternatively in parallel and in phase opposition, the durations of each feeding manner being unequal.

6. Radio-guide transmitting system comprising a first aerial having a vertical symmetry axis, means for transmitting by said first aerial a figure of 8 radiation field, means for reversing the phase of said diagram at dot and dash rhythm, a second aerial having a common vertical symmetry axis with said first aerial, and means including switching means connected to said second aerial for transmitting by said second aerial alternatively a modified figure 8 radiation field having identical instantaneous phase 70 in all directions, and a figure of 8 radiation field analogous to that of said first aerial but perpendicular thereto, means for feeding said aerials by a high frequency current, and means for changing by 90° the phase between the currents 75

in both aerials synchronously with said switching in the second aerial.

7. Radio-guide transmitting system comprising a first aerial having a vertical symmetry axis, means for transmitting by said first aerial a figure of 8 radiation field, means for reversing the phase of said field at dot and dash rhythm, a second aerial having a common vertical symmetry axis with said first aerial, and means including switching means connected to said second aerial for transmitting by said second aerial alternatively a modified figure 8 radiation field

having identical instantaneous phase in all directions, and a figure of 8 radiation field analogous to that of said first aerial but perpendicular thereto, means for feeding said aerials by a high frequency current, a loop inserted in the feeding connection of said second aerial, the length of said loop being equal to a quarter wave length of the feeding current, and a switch for alternatively short-circuiting and opening said loop synchronously with said switching in the second aerial.

YVES ROCARD.
